UNITED STATES PATENT OFFICE

JAMES B. NEIL, OF KNOXVILLE, TENNESSEE

NEEDLE-LOCKING DEVICE FOR SYRINGES

Application filed February 8, 1929. Serial No. 338,534.

The present invention relates to syringes, and particularly to means for locking a needle to syringes.

It has been found in medical practice that often the needle base of syringes and hypodermics accidentally becomes dislodged, and either falls off or permits the escape of the fluid or the entrance of air into the fluid. The consequences resulting are not only annoying, but, in a great many cases, dangerous to the patient.

The object of the invention is to provide an air-tight and fluid-tight coupling.

Another object of the invention is to provide a coupling which is simple in operation, and can be easily and quickly manipulated.

Another object of the invention is to provide a device which can be cheaply manufactured, and is not prohibitive in price.

Still another object of the invention is to provide means whereby a positive connection may be obtained, where the failure of such might have extremely harmful results.

The invention can be applied to a number of surgical and clinical instruments where a secure joint is necessary and required, for example, the cystoscope and urethroscope, where the material is of such consistency as to permit the making of grooves therein.

In the drawings:—

Figure 1 is a side view of the syringe partly in cross section.

Figure 2 is an enlarged view in cross section of the locking device.

Figure 3 is a plan view of the needle base showing the arms.

Figure 4 is a perspective view of the barrel showing the slots through the abutment into the groove.

Figure 5 shows a modified form, in which the groove extends but partly around its circumference.

Referring specifically to the drawings, 1 is the barrel, and 2 is the piston, which may be formed of glass, metal, hard rubber, or other suitable material. The piston 2 has at one end the grip 3 of any desired form.

At the end of the barrel where the piston is inserted is a circumferential enlargement 4, which is interiorly grooved as at 5, wherein

is seated a split ring 6. This element is fully explained and claimed in Letters Patent No. 1,343,787, issued June 15th, 1920.

At the needle end of the barrel is a shoulder 7 from which extends the nipple 8, the latter preferably, though not necessarily, being slightly tapered. A passageway 9 runs from the interior of the barrel through the said nipple.

Formed at the innermost end of the nipple 8 is a groove 10, bordered on one side by the shoulder 7, and on the other side by an abutment 11. It will be noted that the side 12 of the abutment, adjacent the groove, is slightly undercut and forms an acute angle. 65 Slots 13 are provided on opposite sides of the nipple and extend through the abutment into the groove.

The needle base 14, which is usually formed of metal, but may be of other suitable material, contains a socket 15 shaped exactly to fit the nipple 8. A passageway 16 runs from within the socket to the needle and connects with the passageway 9 in the nipple. Integrally or otherwise attached to the needle base are arms 17 hooked at their ends, as at 18, to fit the acute angle in the side 11 of the abutment adjacent the groove. These arms are slightly flexible to allow expansion when slipped over the tapering nipple and through the slots in the abutment. It is important that they not be too flexible so as to become bent or mis-shaped.

The said arms will be in a position to engage the groove when the tapered nipple is substantially against the bottom of the socket in the needle base. When in this position, the desired air-tight and fluid-tight joint is made, and by turning the arms into the groove, the positive locking means is provided.

Two indentations 19 are formed on the opposite sides of the needle base to provide means for grasping with the thumb and fingers.

A modified form of the invention is shown in Figure 5. The groove 10 extends only around part of the circumference of the nipple, and in this way a stop is formed.

To assemble the device the needle base is

grasped at the indentations and fitted over the nipple, the arms are slipped along the nipple and through the slots in the abutment, and a quarter turn of the needle base is made. 5 In this way the needle base is positively secured to the barrel without fear of the possibility either of becoming entirely dislodged, or loose, whereby leakage might occur.

Such structural changes, which call merely 10 for mechanical skill, are, of course, to be considered as within the range of my invention.

I claim:—

1. In a syringe, the combination of a barrel having a nipple provided with a groove between the barrel and the free end of said 15 nipple, a needle carrier adapted to engage said nipple, and resilient groove-engaging means on said carrier to enter the groove when said carrier engages said nipple and hold the parts in operative relation.

2. In a syringe, the combination of a barrel having a nipple provided with a groove between the barrel and the free end of said 25 nipple, a needle carrier adapted to engage said nipple, and spring arms on said carrier having groove-engaging members to enter the groove when said carrier engages said nipple and hold the parts in operative relation.

3. In a syringe, the combination of a barrel having a nipple provided with a groove between the barrel and the free end of said 35 nipple, a needle carrier adapted to engage said nipple by a straight-line movement, resilient means on said carrier registering with the groove upon engagement of said carrier with said nipple, said resilient means adapted to engage the groove and lock the parts in operative relation upon relative rotation of said carrier and nipple.

4. In a syringe, the combination of a barrel having a nipple provided with a groove between the barrel and the free end of said 45 nipple, a needle carrier adapted to engage said nipple by a straight-line movement, spring arms on said carrier registering with the groove upon engagement of said carrier with said nipple, said spring arms adapted to engage the groove and lock the parts in 50 operative relation upon relative rotation of said carrier and nipple.

5. In a syringe, the combination of a barrel having a nipple provided with a groove between the barrel and the free end of said 55 nipple, a needle carrier adapted to engage said nipple by a straight-line movement, spring arms having groove engaging hooks on said carrier registering with the groove upon engagement of said carrier with said 60 nipple, said spring arms adapted to engage the groove and lock the parts in operative relation upon relative rotation of said carrier and nipple.

6. In a syringe, the combination of a barrel having a nipple, a shoulder on said nipple

spaced from said barrel to form a groove, a needle-carrier having a nipple-engaging socket to engage said nipple by a straight-line movement, and a plurality of spring arms on said carrier provided with shoulder engaging means to lock the parts in operative relation upon relative rotation of said nipple and carrier.

7. In a syringe, the combination of a barrel having a nipple, an undercut shoulder on 75 said nipple spaced from said barrel to form a groove, a needle-carrier having a nipple-engaging socket to engage said nipple by a straight-line movement, and a plurality of 80 spring arms on said carrier provided with shoulder engaging hook portions to lock the parts in operative relation upon relative rotation of said nipple and carrier.

8. In a syringe, the combination of a barrel having a nipple, a shoulder on said nipple 85 spaced from said barrel to form a groove and provided with a plurality of symmetrically disposed notches, a needle-carrier to engage said nipple, and spring arms on said carrier having hook portions to enter said notches and upon relative rotation of said nipple and carrier lock the parts in operative relation.

9. In a syringe, the combination of a barrel having a nipple, a notched shoulder on 95 said nipple spaced from said barrel to form a groove the bottom of which is substantially in the plane of the wall of said nipple, a needle carrier having a nipple-engaging socket, and resilient groove-engaging members on said carrier adapted to ride the wall of said nipple through the notches in said shoulder, and upon relative rotation of said nipple and carrier engage the groove and lock the parts in 100 operative relation.

10. In a syringe, the combination of a barrel having a nipple, a notched shoulder on 110 said nipple spaced from said barrel to form a groove the bottom of which is substantially in the plane of the wall of said nipple, a needle carrier having a nipple-engaging socket, groove-engaging members on said carrier adapted to ride the wall of said nipple through the notches in said shoulder, and upon relative rotation of said nipple and carrier engage the groove and lock the parts in 115 operative relation, and a stop in said groove to limit rotation of the parts.

11. In a syringe, the combination of a barrel having a tapered nipple, a notched shoulder on said nipple spaced from said barrel to form a groove the bottom of which is substantially in the plane of the wall of said nipple, a needle carrier having a tapered nipple-engaging socket, and resilient groove-engaging members on said carrier adapted to ride the wall of said nipple through the notches in said shoulder, and upon relative rotation of said nipple and carrier engage the groove and lock the parts in 120 operative relation.

12. In a syringe, the combination of a barrel having a nipple, a notched shoulder on said nipple spaced from said barrel to form a groove the bottom of which is substantially in the plane of the wall of said nipple, a needle carrier having a nipple-engaging socket, finger grips on said carrier, and resilient groove-engaging members on said carrier adapted to ride the wall of said nipple through the notches in said shoulder, and upon relative rotation of said nipple and carrier engage the groove and lock the parts in operative relation.

13. A syringe barrel having a nipple projecting therefrom and provided with a notched shoulder to form a groove between the barrel and the free end of the nipple, the outer wall of the nipple being in substantially the plane of the bottom of the groove.

14. A needle carrier for syringes having a nipple-engaging socket provided with finger grips, and resilient syringe-engaging arms projecting from the said carrier.

15. A needle carrier for syringes having a nipple-engaging socket provided with finger grips, and resilient syringe-engaging arms projecting from the said carrier and having inwardly-turned hook portions at their ends.

30 In testimony whereof I have hereunto set my hand.

JAMES B. NEIL.
